CLAIM

We claim the ornamental design for a cover for a probe or the like, as shown and described.

DESCRIPTION

FIG. 1 is a top perspective view of a cover for a probe or the like according to our new design;

FIG. 2 is a bottom perspective view thereof;

FIG. 3 is a side elevation cross-section view thereof;

FIG. 4 is a detail view of a portion of thereof indicated in FIG. 3;

FIG. 5 is a bottom plan view thereof;

FIG. 6 is a side elevation view thereof; and,

FIG. 7 is a top plan view thereof.

The broken lines immediately adjacent to the shaded areas depict boundaries of the claim and form no part of the claimed design. All other broken lines and the areas within them depict portions of the cover for a probe or the like that form no part of the claimed design.
